P. GADECKI

MECHANICAL TOY

Filed Jan. 6, 1923.

UNITED STATES PATENT OFFICE.

PHILIP GADECKI, OF MYSTIC, IOWA.

MECHANICAL TOY.

Application filed January 6, 1923. Serial No. 611,133.

To all whom it may concern:

Be it known that I, PHILIP GADECKI, a citizen of Poland, residing at Mystic, in the county of Appanoose and State of Iowa, have invented certain new and useful Improvements in Mechanical Toys, of which the following is a specification.

This invention relates to new and useful improvements in mechanical toys and has 10 particular reference to a toy cannon of the catapult type.

An important object of the invention is to provide a toy of the type above set forth having a hammer and trigger mechanism 15 of novel and improved form which are simple in construction and reliable in operation.

A further object of the invention is to provide a simple adjusting means for varying 20 the firing range of the toy.

Other objects and advantages of the invention will be apparent during the course of the following description.

In the accompanying drawings forming 25 a part of this specification and in which like numerals are employed to designate like parts throughout the same,

Figure 1 is a side elevational view, partly 30 in section, of the toy embodying my invention,

Figure 2 is a top plan view of Figure 1,

Figure 3 is a bottom plan view of Figure 1,

Figure 4 is a vertical sectional view taken 35 on line IV—IV of Figure 1,

Figure 5 is a fragmentary vertical sectional view taken on line V—V of Figure 1,

Figure 6 is a front elevational view of a 40 form of target used in connection with the toy set forth in Figures 1 to 5, and

Figure 7 is a vertical sectional view taken on line VII—VII of Figure 6.

Referring more in detail to the accompanying drawings, and particularly to Figures 1 to 5, there is illustrated a toy cannon embodying a carriage or mount 1 having secured adjacent its forward end, as by dowel pins 2, depending spaced lugs 3 which constitute journal bearings for the 45 axle 4 having solid wheels 5 splined thereon. The carriage or mount 1 is further provided with a rectangular opening 6, the use of which will be apparent as the description proceeds, and a longitudinally extending guide slot 7 positioned adjacent its

rear end and adapted for receiving the perpendicular, squared shank 8 of the enlarged head 9 which is carried by the cam block 10. This cam block is further provided with a handle 11 that extends rearwardly of the carriage or mount and provides a manual control for longitudinally moving the cam surface 12 of the block in respect to the carriage or mount 1 for raising or lowering the rear end of the same to 60 vary the range of fire of the cannon.

A barrel 13 is rigidly supported upon the carriage or mount 1 adjacent its forward end by the perpendicular post 14 and at its rearward end by the plate 15 having a 70 brace bar 16 as shown. The plate 15 is provided with an aperture 17 that aligns with the bore 18 of the barrel 13 and constitutes a rest for the missile or projectile 19 when placed in the cannon in readiness 75 for being ejected therefrom. A sight 13¹ is provided at the forward end of the barrel to aid in directing the fire in the usual manner.

The ejecting mechanism embodies a hammer 80 consisting of a hammer plate 20 secured to the substantially U-shaped swinging support 21 which is provided with side legs 22 having free ends 23 bent laterally to pivotally engage the staples 24 driven into the carriage or mount 1 in juxtaposition to the plate 15 and a cross bar 25 that is bent to form an eye 26 at a point intermediate its ends. This eye is adapted to extend through the rectangular opening 6 when the hammer 90

is moved to its cocked position. Connected to opposite sides of the hammer plate 20 as at 27 are forwardly extending flexible cords 28 which are directed through openings 29 provided in the plate 15 and ride upon pins 95 30 placed therein. The forward ends of the flexible cords are connected to spiral springs, or the like, as designated by the numeral 31 which are secured at their other ends to the forward ends of the carriage or mount 1 as 100 by eye-screws 32. The flexible cords 28 and spiral springs 31 are adapted to forcibly draw the hammer plate 20 against the rear face of the plate 15, as indicated by the arrow line in Figure 1, when the said 105 hammer plate has been released from its cocked or set position as shown in both Figures 1 and 2.

The trigger mechanism embodies a trigger lever 33 pivotally attached to the under 110

- face of the carriage or mount 1 as at 34 and extending transversely thereof through the guide strap 35 to terminate in the projecting eye or trigger 36, the said lever 5 being bent as at 37 to form a substantially U-shaped loop that is connected to the eye 38 carried by the trigger keeper 39. This trigger keeper is guided in its movement by the staples 40 and 41 and is adapted to be moved into and out of engagement with the eye 26 which is carried by the swinging support 21 and projects through the rectangular opening 6 when the hammer is in its cocked position.
- 15 A suitable form of target is shown in Figures 6 and 7 and embodies legs or supports 42 having a cross bar 43 connected therebetween. Connected to the legs or supports 42 and positioned rearwardly of the cross bar 43 is a rod 44 which is adapted to pivotally support the target plates 45. The front face of the target plates are preferably provided with configurations or designs as shown in Figure 6. These target plates are adapted to swing rearwardly as indicated by the arrow line in Figure 7 when struck by the flying missile fired from the cannon.
- 20 The operation of the device is as follows: 30 The hammer is drawn downwardly into the position as shown in Figures 1 and 2 with the eye 26 projecting through the rectangular opening 6 to be engaged by the trigger keeper 39 when the trigger lever is moved to its full line position as shown in Figure 2, thus placing the spiral springs 31 under tension. A missile or projectile 19 is placed in the aperture 17 with its forward end protruding into the bore 18 of the barrel 25 35 40 45 50 55 60 65 70 75 80 85 90 95 100 105 110 115 120 125 130
13. The striking end of the projectile is preferably positioned slightly rearwardly of the plate 15 as shown. Upon moving the trigger lever 33 to its dotted line position as shown in Fig. 2, the trigger keeper 39 is withdrawn from the eye 26 to release the hammer, the hammer plate 22 is swung upwardly by the spiral springs 31 to strike the protruding end of the projectile thus driving it through the bore 18 to be discharged therefrom.
- It is to be understood that the form of my invention herewith shown and described is to be taken as the preferred example of the same, and that various changes in the shape, size, and arrangement of parts may be resorted to without departing from the spirit of the invention or the scope of the subjoined claims.
- Having thus described the invention, I claim:
1. In a device of the character described, a carriage having supporting wheels at its forward end, a longitudinally extending slot formed adjacent its rear end, a cam block associated with said slot for raising and lowering the rear end of said carriage, a cannon barrel mounted on said carriage, a hammer pivotally mounted on said carriage rearwardly of said barrel, a trigger mechanism mounted on the under surface of said carriage and adapted to retain said hammer in its cocked position, and resilient means associated with said carriage and hammer for swinging said hammer upwardly when the same is released by the trigger mechanism, the said resilient means comprising springs secured at one of their ends to said carriage, and flexible cords secured to the free ends of said springs, the said cords being attached to the hammer at their other ends.
2. In a device of the character described, a carriage, a cannon barrel supported at its rear end above said carriage by a plate member, said plate member having openings positioned one on either side of said barrel, transverse pins positioned in said openings, a hammer swingingly connected to said carriage in proximity to the base of said plate member, tension springs secured to the forward end of said carriage, flexible members secured to the free ends of said springs slidably engaging said pins and connected to said hammer, and a trigger mechanism carried by said carriage for retaining said hammer in its cocked position against the tension of said springs.
3. In a device of the character described, a carriage, a cannon barrel supported above said carriage, a hammer pivotally connected to said carriage rearwardly of said barrel, said hammer comprising a substantially U-shaped support, and a hammer plate secured to said support, tension means for normally retaining said hammer in its uncocked position, and a trigger mechanism for retaining said hammer in its cocked position against the pull of said tension means.
4. In a device of the character described, a carriage, a cannon barrel supported above said carriage, a hammer pivotally connected to said carriage rearwardly of said barrel, said hammer comprising a substantially U-shaped supporting member, a loop formed in said supporting member, and a hammer plate secured to said support, tension means for normally retaining said hammer in its uncocked position, and a trigger mechanism for engaging said loop to retain said hammer in its cocked position against the pull of said tension means.
5. In a device of the character described, a carriage, a cannon barrel supported above said carriage, a hammer pivotally connected to said carriage rearwardly of said barrel, said hammer comprising a substantially U-shaped wire supporting member, a loop portion formed in said wire support, and a hammer plate secured to said support, tension means for normally retaining said ham-

mer in its uncocked position, and a trigger mechanism adapted for retaining said hammer in its cocked position against the pull of said tension means, said trigger mechanism comprising a lever pivotally connected to said carriage, a loop portion formed in said lever, and a trigger keeper connected to said loop portion adapted for engaging the loop portion formed in the hammer supporting member when the latter is moved ¹⁰ to its cocked position.

In testimony whereof I affix my signature.

PHILIP GADECKI.
